[57] CLAIM

The ornamental design for a deck of playing cards with
segmented numbers, as shown and described.

DESCRIPTION

FIG. 1 is a plan view of the front of the diamonds suit
of a deck of playing cards with segmented numbers
showing a first embodiment of my new design;

FIG. 2 is a plan view of the front of a representative
card of the spades suit of my new design;

FIG. 3 is a plan view of the front of a representative
card of the hearts suit of my new design; and

FIG. 4 is a plan view of the front of a representative
card of the clubs suit of my new design.

The back of the playing cards is conventional.

FIG. 1

FIG. 2

FIG. 3

FIG. 4
